UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

HOODED JOURNAL-BOX LID AND METHOD OF MAKING SAME.

Application filed February 4, 1922. Serial No. 334,174.

To all whom it may concern:

Be it known that I, CLAUS J. WERNER CLASEN, a citizen of the United States of America, residing in Davenport, Iowa, am the inventor of certain new and useful Improvements in Hooded Journal-Box Lids and Methods of Making Same, of which the following is a true, complete, and concise description.

10 My invention relates to lids for journal boxes and the like. It also relates to methods of making such articles. One of the objects of my invention is to provide a hooded pressed steel journal box lid which shall substantially prevent the accumulation of 15 dirt in the box which occurs with the present type of hooded lid.

Among other objects of my invention are: 20 to provide a journal box lid of the hooded type which shall be capable of ready and economical manufacture and which shall be not only rugged when in use, but readily repaired when deformed; and to provide a hooded journal box lid comprising a minimum number of parts.

25 The hooded type of journal box lid has certain recognized advantages as compared with the non-hooded type. I have found, however, that the pressed hoods of lids prior to my invention, permit a circulation of air from outside the box into the interior of the same.

30 As journal boxes are used in an extremely dusty place, this circulation of air carries much dust into the interior of the boxes and the dust is caught by the oil in the box and retained therein, thus increasing the wear on the journals and bearing brasses.

According to my invention, this circulation of air is prevented by making the body 35 of the lid to cover the box closely over the entire top of the box when closed and forming the hood on a part lying above the body of the lid. In manufacturing a lid according to my invention, I first make a blank by 40 pressing or stamping from metal sheet or plate, said blank having a body of the same outline as the box and adapted when closed to cover the box closely at all points thus 45 preventing any circulation of air over the edge of the box when the lid is in use. Integral with the part of the blank designed to act as the body or lid proper is a portion 50 designed to form the hood and the hinge eyes. The blank is then bent back on itself

so that the latter portion of the blank is folded or bent back on itself, so that the latter portion of the blank partly overlies the body of the lid. The hinge eyes are made at the time the blank is folded or bent back on itself. The two parts of the blank are then secured together.

The novel features of my invention are pointed with much particularity in the appended claim. The invention itself, however, will best be understood from the following description taken with the accompanying drawings in which:

Fig. 1 is the plan view of a journal box lid according to my invention.

Fig. 2 is a section on the line 2-2 of Fig. 1.

Fig. 3 is a view taken from the front of Fig. 1, parts being shown in elevation and parts in section on the line 3-3 of Fig. 1.

Fig. 4 is a plan view of a blank used in making a journal box lid according to my invention and illustrating the blank as it appears at an intermediate point in the process of manufacturing the lid.

Fig. 5 is a section on the line 5-5 of Fig. 4.

Referring in detail to the drawing, 1 indicates the body of the lid which is preferably made of sheet steel or the like. A down-turned flange 2 surrounds body 1 on three sides. This flange serves to stiffen the lid and also to hold it in place when in use. The front edge of lid 1 is formed with a finger piece 3^a. The body 1 has a symmetrical U-shaped depression 3 therein for imparting rigidity to the lid. The non-depressed portion 4 which projects within the U-shaped depression serves as the support of the forward end of the spring 5. The rivet 5^a secures the front end of spring 5 to flat part 4.

Integral with the body 1 along the rear edge of the body are two eyes 6, 6. A hood 7 extends along the inner edges of the eyes, but is disconnected from body 1 except for the connection through the eyes 6. This hood, 7, is high at its rear end as most clearly appears in Fig. 2, but slopes downwardly from rear to front and also contracts laterally from rear to front. From this combined sloping and contracting of hood 7 it results that the hood is brought down to a shallow channel 7^a at its front part. The channel 7^a just fits the spring 5.

2 at a point slightly to the rear of rivet 5^a. Extending forward from the eyes 6, 6 and integral with the hood 7 along the sides of the hood are two flat wings 8, 8, which 5 lie in contact with the top of body 1. Consequently, when wings 8, 8 are fastened down as illustrated to body 1 by rivets 8^a, 8^a, one on each side of channel 7, the channel acts as a strap to hold the spring 5 10 tight against the body of the lid and thus forms a fulcrum for the spring.

In forming a lid or cover according to my invention, the blank 1^a (Figs. 4 and 5) is pressed or stamped from a suitable sheet 15 or plate and pressed to provide a body 1 having the features previously described. Along its rear edge, blank 1^a is bent downwardly forming a flange 9. Flange 9, however, inclines outwardly and rearwardly 20 from the body 1 and does not extend downwardly as far as flange 2. Immediately to the rear of inclined flange 9, blank 1^a is cut away as illustrated at 10, Fig. 4, for a space extending somewhat on each side 25 of the centre line of the blank. On each side of space 10, however, the blank 1^a comprises strips 11 which are integral with and extend rearwardly from flange 9. Each of strips 11 comprises a flat portion 12, next 30 to the flange 9. Portions 12 are flat and parallel to body 1. At the rear edge of each flat portion 12 the strip is bent downwardly forming an inclined portion 13. Following inclined portion 13 in each strip 35 is a second flat portion 14 parallel to part 12 and which connects in turn with a downwardly and outwardly inclined part 15. Part 15 connects in turn with half round part 16, which curves around so that its rear 40 part is directed toward the plane of body 1. Half round section 16 is followed in the rearward direction by flat part 17. Owing to the circular arc covered by the portion 16, flat parts 17 in the blank lie in a 45 plane at an angle of about 45 degrees to the plane of body 1. Flat part 17 connects with a curved portion 18 and curved part 18 connects in turn with one of the flat wings 8, previously mentioned. It is apparent from Fig. 5 that hood 7 and channel 7^a unite each pair of parts 16, 17, 18 and 8. Moreover, the concavity of the hood is on the opposite face or side of the blank from that of the body portion. These parts having 50 been pressed into the shapes illustrated in Fig. 5, are held rigidly in the relative positions shown by the stiffening action of hood 7. Moreover, each pair of parts 12 and 13 are stiffened by a flute 12^a extending from the rear edge of flange 9 to the front end of the corresponding flat part 14. It is apparent that only the flat parts 14 are unstiffened of all the parts between the flange 9 and the channel 7^a.

60 65 In manufacturing a lid according to my

invention, the blank is first struck up into the shape illustrated in Figs. 4 and 5, and then the hood 7 and the parts directly attached thereto are bent over into the position illustrated in Figs. 1, 2, and 3, wherein 70 the concavity of the hood is on the side toward the body portion and a chamber is formed to receive the spring 5. The flat part 14 being unstiffened is readily bent into a half round form, parts 14, 14 and 15, 15 of the blank combining to form the hinge eyes 6, 6 of the finished lid or cover. 75

The hood 7 and connected parts being in the position shown in Figs. 1, 2, and 3, the spring 5 is put in place as illustrated and riveted to the body 1 of the lid by rivet 5^a. The wings 8, 8 are then riveted to body 1 by rivets 8^a, 8^a. While I have illustrated the parts 5 and 8, 8 as fastened to the body 1 by means of rivets, I do not limit myself to this, as other means, as for example, spot welding, may be employed. 80 85

85 It will be seen that the outline of the body is not cut away beneath the hood 7, but that the flange 9 to which the hinge eyes are attached runs straight across between adjacent corners of the lid and is adapted to close the journal box on which the lid is used so as to prevent circulation of air 90 over the rear edge of the box when the lid 95 is closed.

95 It will be seen that I have provided a lid 100 for use on journal boxes or the like which may be readily manufactured and which is rugged in use, but which has a minimum of parts and is readily repaired if deformed. It will be seen also that a lid according to my invention not only has the advantages mentioned together with those of the usual hooded type, but comprises a hood and a body acting when in closed position to prevent circulation of air over the edge of the box. 105

Having thus described my invention, I 110 claim:

1. A journal box lid comprising integral body, hinge eyes and hood, all of metal plate, said body underlying said hood as far as the line of the box cooperating with the lid whereby dust is substantially excluded 115 from the journal box when the lid is closed over the same.

2. The method of making a hooded journal box lid comprising pressing out of a single metal plate, a concave body portion and a concave hood portion connected by spaced strips only, the concavities of said portions being pressed in opposite sides of the blank and bending said hood portion over on said body portion and making said strips into hinge eyes. 120

3. The method of making a hooded journal box lid comprising pressing out of a single metal plate a body portion and a concave hood portion spaced apart but connect- 125 130

ed by strip material, said body having a flange thereon lying on one side of said body, and the concavity of said hood opening on the other side of said body, bending said hood portion over on said body portion and forming the last part of said strip material into a hollow cylindrical form.

4. The method of making a hooded journal box lid comprising pressing out of a single

metal plate a body portion having a substantially square outline and a concave hood portion connected by strip material only bending said hood portion over on said body portion with the concavity in the hood facing the body portion of the lid and forming the last part of said strip material into a hollow cylinder.

CLAUS J. WERNER CLASEN.
